UNITED STATES PATENT OFFICE.

GEORGE J. FITZPATRICK, OF CHICAGO, ILLINOIS.

CAN-OPENER.

1,244,972.

Specification of Letters Patent. Patented Oct. 30, 1917.

Application filed December 17, 1914. Serial No. 877,797.

To all whom it may concern:

Be it known that I, GEORGE J. FITZPATRICK, a citizen of the United States, residing at Chicago, in the county of Cook and State 5 of Illinois, have invented certain new and useful Improvements in Can-Openers, of which the following is a specification.

The present invention relates to a can opener used for the purpose of cutting the 10 surface of tin or other cans or receptacles, for the purpose of opening the same.

The objects of the present invention are to construct a can opener of the character described which is cheap and simple of construction, easy of manipulation and operation and durable as respects wear.

A further object of the invention is to 15 so arrange the parts of the device as to permit the easy severance of the surface of a 20 square can or receptacle.

A further object of the invention is to 25 arrange the parts of the opener so that they may be assembled or disassembled as desired without trouble and without disorganization.

The invention further consists in the features of construction and combinations of parts hereinafter described and claimed.

In the drawings:

30 Figure 1 is a plan view showing the can opener of the present invention in operative position upon a can;

Fig. 2 is a section on line 1—1 of Fig. 1 seen from the rear of the device;

35 Fig. 3 is a detail of the cutting member and associated parts; and

Fig. 4 is a perspective of the parts shown in Fig. 3.

The art to which the present invention 40 relates deals with devices of the character which may be termed kitchen implements. It is essential to devices of such a nature that they be cheap and simple of construction, for owing to the fact that they are 45 generally used by the housewife, complex or easily disorganized mechanism would render them impractical, and owing to the fact that they are part of the equipment of a household, and in a sense a household necessity, 50 the cheapness in price is important, it being of material benefit to the public at large to secure implements of this kind at a small cost. Therefore the more the manufacturing cost of these articles is lowered the lower 55 will be the selling price, and the general public will thereby benefit. It is, therefore,

extremely important in arts of this kind to render the device cheap and simple both as to cost and use. Difficulty has also been experienced in this art in producing a practical opener which will be operative with respect to square cans. The present invention, it is believed, fulfills the requirements and demands of the art as above outlined.

Referring now to the drawings, the device 60 may be said to consist generally of two parts, first the actuating portion designated by the numeral 5 in the drawing, and the operative portion which is designated by the numeral 6 in the drawing. The actuating portion 65 consists of a single piece of material in the form of a plate or bar 7. It is, of course, understood that the opener as an entirety, and as to individual parts, may be of any 70 suitable size and may be made of any suitable material. The actuating member embodies a handle 8 at one end and at the opposite end is formed with a tine or prong 9 adapted to be inserted through the surface of the receptacle being operated upon. The 75 body of the member 5 is formed with a longitudinal slot 10 terminating in an enlarged opening 11, the point of juncture of said slot with said opening, being contracted as at 12. If desired, at the extreme end of 80 the handle an opening 13 may be formed to create a cap removing implement for bottles. The part 5 is termed the actuating portion 85 since this is the part that is grasped by the operator and moved by his influence. 90

The part 6 has been designated as the operative portion since it is this part which is influenced by the movement of the actuating portion to perform the cutting operation. This part 6 consists of a disk 14 lying 95 on the under side of the portion 5, and depending from the disk is a cutting member 15 and a guiding member 16. A headed rivet 17 is secured to the disk, the shank portion 18 resting in the slot 10 with the 100 head overlying the slot, and as shown the disk has oppositely disposed upwardly extending ears 19 thereon. The shank 18 when the device is assembled travels in the slot 10 of the actuating member 5 and has a sliding and turning movement therein. As stated, this slot 10 is contracted at one end as at 12 and by means of such contraction disengagement of the actuating and operating portions of the device is prevented under the 110 normal conditions, but these portions may be readily and quickly assembled and disas-

sembled when desired by simply pulling the shank 18 through the contracted portion 12 of the slot 10 so that the head 17 can pass through the opening 11, thus enabling the operating portion to be removed for the purpose of sharpening the cutting member, etc. It is, of course, understood that the actuating part 5 possesses sufficient spring qualities to enable the passing of the shank 18 through the contracted portion 12 of the slot 10, as described.

In can opening operations it is extremely desirable that some guiding means be provided which rest against the outside of the can and maintain the cutting member an equidistance from the center of the can during the cutting operation. Since in practice it is impossible to insert the prong 9 each time at the center of the can, and if some means are not provided for moving the cutting member with respect to the actuating member the cutting member will follow an elliptical path, owing to the prong 9 not being in the center of the can, with the result that the cutting member frequently strikes the side of the can and prevents completion of the cutting operation. In the present invention a guide is provided in the form of a depending tongue 16, heretofore referred to, and by referring to Figs. 3 and 4 it will be seen that this tongue lies to the side of the cutting member as well as to the rear thereof, and is angularly disposed with respect to the cutting member so that it is spaced apart from said member a greater distance at the lower end of the member than the upper end.

In use, if a circular can is being cut the prong 9 is inserted, the operating member 40 moved in the slot 10 until the lower end of the guide 16 engages the side of the can, it being observed that the guide is somewhat longer than the cutting member and extends below the same. When the guide has been 45 brought into engagement with the side of the can, by pressing downward the cutting member is forced through the surface of the can to be cut, and then the operator by applying pressure to the actuating member turns the device about the prong 9 as a center. If the prong 9 is in a position other than the axial center of the can it will make no difference since the guiding member 16 traveling against the side of the can will 50 pull the operating member 6 in the slot 10 whereby the cutting member will remain an equidistance from the edge of the can during the entire operation and efficiently cut the same.

60 I so configure the cutting member as to bend the edges of the cut metal downward during the cutting operation so that a smooth metal surface is presented after the can is cut leaving no sharp edges which are dangerous in further handling of the can. When

a square can is being opened the device is used in the manner shown in Fig. 1. The prong 9 is first inserted at one side of the can and a cut made from a point opposite the point of insertion of the prong around 70 to the opposite side, that is half way around the can or approximately half way. The prong is then inserted on the opposite side of the can and a similar operation takes place.

75 It would be a matter of impossibility to open these square cans with an opener of the type shown in the present invention, without the use of a guide member and the guide member must be correctly arranged 80 with respect to the cutting member or it will bind on turning a corner and prevent proper operation of the cutter. When positioned, as shown in the drawings of the present application, any binding action is entirely 85 eliminated. The reason for diagonally disposing the guide member 16 with respect to the cutter is that when the cutter is forced into place the entire length of the guide member will not engage the can, but only 90 the upper portion, as engagement along the entire length of the guide would be undesirable by reason of the fact that a binding might result in operation. The function of the ears 19 is as follows:

95 It is desired in positioning the operating member to have the cutter 15 extend at approximately right angles to the slot 10, and by grasping these ears 19 the operator can quickly and easily turn the disk 14 into 100 position to so center the cutting member. These ears moreover operate in the nature of stop members to prevent a turning of the cutting member clear around to one side of the slot 10 in which position it would not 105 operate. By providing such stop means the housewife can never become confused by reason of such a position being assumed by the cutting member and by the failure of the device to work owing to such assumed 110 position.

The ears serve a further useful function, in that they enable the operating portion to be readily and quickly moved up or down in the slot 10, to place the cutting member 115 at any desired point on the surface of the can.

I claim:

1. In a device of the class described, the combination of an actuating portion of 120 spring material formed with a longitudinal slot, an operating portion having a part arranged to slide and turn in said slot, a cutting member depending from the operating portion, a guide member to the rear of 125 the cutting member and carried by the operating portion and said slot being restricted at one point and enlarged directly beyond said restricted portion to prevent accidental separation of the actuating and op- 130

- erating portions and permit intentional separation thereof, substantially as described.
2. In a device of the class described, the combination of an actuating portion and an operating portion, said actuating portion having a longitudinal slot therein, said operating portion having a part arranged to slide and turn within said slot, a cutting member depending from the operating portion, a guide member depending from the operating portion and stop members carried by said operating portion and arranged to engage the actuating portion to limit the turning movement of the operating portion with respect to the actuating portion, substantially as described.
3. In a device of the class described, the combination of an actuating portion and an operating portion, said actuating portion having a longitudinal slot, said operating portion being arranged to slide and turn in said slot, a cutting member depending from the operating portion, a guide member to the rear of the operating portion, and stop members in the form of oppositely disposed upwardly extending ears carried by the operating portion for limiting the turning movement of the operating portion with respect to the actuating portion, substantially as described.
4. In a device of the class described, the combination of an actuating portion formed with a longitudinal slot, an operating portion consisting of a disk arranged to lie below the actuating portions, a headed stem extending from the disk with the shank thereof traveling within the slot, a cutting member depending from the disk and lying medially thereof, a guide member in the form of an ear depending from the disk and lying medially thereof and said guide member being located to the rear and side of the cutting member, and members carried by said disk acting as stop members to limit the turning movement of the operating member with respect to the actuating member, substantially as described.
5. In a device of the class described, the combination of an actuating portion and an operating portion, said actuating portion consisting of a plate formed with a longitudinal slot, an operating member arranged to slide and turn in said slot, a depending cutting member and a depending guide member from said operating member and formed integral with said operating member, a stud extending from approximately the center of said operating member and into the slot of said actuating member, said cutting member being located to the front and in substantial alinement with said stud, and an upwardly extending ear integral with said operating member and adapted to engage the side of the actuating member to serve as a stop for limiting the turning movement of the operating member, substantially as described.
6. A device of the class described, consisting of an actuating portion, an operating portion formed of a sheet metal body having portions thereof struck out to provide a cutter, a guide, a stop for determining the extent of rotation of the operating portion with respect to the actuating portion, and means for rotatably and slidably securing the operating portion upon the actuating portion, substantially as described.
7. In a device of the class described, the combination of an actuating portion and an operating portion, said operating portion having a longitudinal slot formed therein, an operating member in the form of a flat metallic plate having two downwardly projecting members struck out therefrom with a web portion between the struck-out members, one of said downwardly projecting members constituting a cutter and the other of said members constituting a flat-faced guide finger, a headed stud extending from the web portion of said plate and through the slot in the actuating portion and having a sliding and turning fit in said slot said cutter lying to the rear of the stud with its cutting edge to one side of the stud, which side is toward the direction of cutting movement of the opener, said guide finger lying in front of the stud and to one side of said stud and said cutter, which side is also in the direction of cutting movement of the opener, and said flat-faced formation of said guide finger giving a line contact between said finger and the curved periphery of a can, and said guide moving in advance of the cutter during the cutting operation, substantially as described.
